UNITED STATES PATENT OFFICE.

BARNEY A. KNUDSON, OF SANTA ANA, CALIFORNIA.

MOLD STRUCTURE.

Application filed August 19, 1922. Serial No. 533,013.

To all whom it may concern:

Be it known that I, BARNEY A. KNUDSON, a citizen of the United States, residing at Santa Ana, in the county of Orange and State of California, have invented new and useful Improvements in Mold Structures, of which the following is a specification.

This invention relates to apparatus for molding concrete walls and other structures and has for its object to provide an extremely simple, practicable, substantial and economical form of knock-down and re-versible concrete molding means.

Another object is to provide a molding structure adapted to be readily installed in different mold boards so as to form during operation a hollow wall or a wall having vertical passage-ways separated horizontally.

Other objects and advantages will be made manifest in the following specification of an embodiment of the invention illustrated in the accompanying drawings, wherein:

Figure 1 is a perspective of one adaptation of the invention.

Figure 2 is a plan of one of the end mold sections.

The invention consists of a set of mold or core members adapted to be arranged within exterior mold boards or panels 2 and 3 which are spaced a suitable distance according to the thickness of the desired wall. The core forming members include inner planks 4 and 5 of any suitable length according to the width of a chamber to be produced in the wall and of suitable height; a practical height of the core planks 4 and 5 being about one foot as this enables the casting of a foot at each step and then the rearrangement and elevation of the core means progressively during the erection of the wall.

Across the upper ends of the core planks 4 and 5 are arranged cross pieces 6 which have vertical apertures 7 through which may be passed dowel or gauge pins 8 which extend down inside of the mold boards 2 and 3 to define the position of these boards laterally. At the ends of the core planks are uprights 9 through which pass bolts 10 securing the cross bars 6 in place.

The upper ends of the uprights 9 are transversely slotted as at 10^a and in the erection of a concrete wall W, in which are

to be formed vertical passageways or vent flues, there is applied to each end of a set of core planks 4 and 5 a semi-cylindrical end core piece 11 which may be of sheet metal. The diametrically opposite edges of each end core piece is formed with inwardly projecting flanges 12 beyond which project lips 13. This forms inwardly extending right angular seats along the edges of the end piece 11 and these seats are adapted to be applied to the corner posts 9 at respective ends of the core planks 4 and 5.

It will be seen therefore, that these planks and the applied end pieces 11 form a substantial core of suitable dimensions and suitably spaced within the mold boards 2 and 3, and which space is adapted to be filled with tamped concrete to form the wall W. The end pieces are held in position by passing cross pins through apertures in the tops of the cross pieces and then lowering the pins 14 into the cross slots 10^a in the tops of the corner posts 9.

From this it will be seen that when a course of mold boards 2 and 3 have been arranged along or around the wall contour or upon a foundation, then the removable core forming members can be readily inserted between the mold boards and properly positioned by the dowel pins 8.

After the necessary number of core structures have been installed around the wall being prepared, then the plastic cement is poured in and tamped and when it has sufficiently hardened the temporary cores are removed by unpinning the end pieces and pulling these upwardly. To obtain a rigid construction vertical wedge blocks 16 may be utilized to support the core planks 4 and 5 and these wedge blocks are pulled from between the planks after the semi-cylindrical end pieces have been pulled.

Further embodiments, modifications and variations may be resorted to within the spirit of the invention as here claimed.

What is claimed is:

1. A knock-down mold device for concrete mold processes, comprising inner core planks, means for supporting the planks in spaced relation between mold boards, and end pieces applicable to the core planks so as to close the ends of the chamber between the planks, said end pieces consisting of semi-cylindrical sheet-metal shells fitting the ends of the core planks, the longitud-

inal edges of the core end shells having inwardly turned flanges forming seats to abut against the ends of the core planks.

2. A knock-down mold device for concrete mold processes, comprising inner core planks, means for supporting the planks in spaced relation between mold boards, end pieces applicable to the core planks so as to close the ends of the chamber between 5 the planks, said end pieces consisting of

semi-cylindrical members fitting the ends of the core planks, the core planks having upwardly extending corner posts with slots in the tops thereof, and fastening pins for attaching the core ends to said corner posts and which pins are adapted to seat in said slots. 15

In testimony whereof I have signed my name to this specification.

BARNEY A. KNUDSON.
